SUPPORT FOR THE CLEANING OF FLOOR COVERINGS

Filed April 1, 1927

INVENTOR

Carlos A. Smith
BY N. E. Deupree
ATTORNEY

UNITED STATES PATENT OFFICE.

CARLOS A. SMITH, OF BELLAIRE, OHIO.

SUPPORT FOR THE CLEANING OF FLOOR COVERINGS.

Application filed April 1, 1927. Serial No. 180,320.

This invention relates broadly to carpet and rug cleansing devices, and more specifically to a support upon which floor coverings may rest while being scrubbed, and to holding means for such coverings.

The primary object of the invention is to provide a supporting bed and means for retaining thereon floor coverings, as carpets and rugs, while the latter are being subjected to the action of a traveling cleansing mechanism.

A further object is to provide a supporting and holding means of the character referred to which is designed especially for use with floor coverings having areas greater than that upon which the scrubbing mechanism employed may operate in its traverse.

A still further object is to provide a device of the character mentioned adapted to be employed in association with traveling scrubbing apparatus of the character disclosed in my co-pending application for Letters Patent, Serial No. 151,349.

In describing the invention in detail, reference is herein had to the accompanying drawings, in which—

Figure 1 is a fragmentary top plan view of the invention illustrating its use;

Figure 2 is a transverse section on line 2—2, Fig. 1;

Figure 3 is an enlarged top plan view of the attaching bar;

Figure 4 is an enlarged face view of the shiftable bar holder;

Figure 5 is a side view of the same; and—

Figure 6 is an enlarged section on line 6—6, Fig. 3.

Referring to said drawings, 1 designates the horizontally disposed supporting bed upon which may rest the floor covering 2, or a portion thereof, while such covering is being acted upon by a traveling, or shiftable, cleansing or scrubbing apparatus which embodies scrubbing rolls 3, indicated in broken lines in Figs. 1 and 2 of the drawings. Said bed 1 is located between the track rails 4 along which the said scrubbing apparatus travels, and located laterally and at opposite sides of the bed are longitudinal channels or troughs 5 which parallel said rails on the inner sides of the latter, as shown.

The bed 1 may be the floor of a room, and the troughs 5 may be formed in such floor, or said bed may be constituted by a built-up

structure which is adapted for mounting 55 upon a floor and which has the troughs formed therein in the locations described.

Mounted within each of the troughs 5, as in brackets or supports 6, is a longitudinally extending bar or rod 7 along which is adjustable a carrier 8 for an end of a transverse bar 9 to which may be attached an edge portion of the floor covering 2 which is to be acted upon. Said bar 9, as herein shown, has struck-up prongs 10 upon which may be 60 impaled said edge portion of the floor covering for securing the latter against shifting movement under the action of the rolls 3 of the scrubbing apparatus. Said bar has tenon-like ends 9^a adapted to be snugly fitted in notches 11 provided in the upper ends of said carriers 8. When not in use, said carriers may be swung from their upright carrying positions to horizontal positions with- 65 in the troughs.

The carrier 8, as herein shown, has divergently inclined resilient legs 8^a which have terminal eye portions 8^b engaged with the adjacent rod 7. Said eyes normally occupy such inclined relation to said rod that they bind upon the latter, as is best indicated in full lines in Fig. 4, but when the legs 8^a are pressed, or sprung, toward each other, as shown in broken lines in said Fig. 4, the carrier may be freely adjusted along said rod 7. 70

The bed 1 will ordinarily have a width for accommodating thereon rugs of the most common room size, as 9 x 12 feet. When a rug of greater width is to be cleansed, it is laid crosswise of the bed with one end thereof coiled into roll form, as shown at 2^a, the roll being disposed within the adjacent trough 5. Thus, when the bed-bearing portion of the rug has been cleansed, the uncleaned portion is drawn upon the bed, and the cleansed portion is coiled into roll form with the roll resting in the opposite trough, whereupon the cleansing mechanism may be passed over said uncleaned portion to complete the cleansing operation. It will be understood that the troughs provide spaces for the reception of the coiled portions of rugs while other portions thereof are subjected to the action of the scrubbing rolls; also that said troughs provide out-of-the-way locations in which the bar supports are positioned.

Means is provided whereby water and

cleansing solution employed is prevented from flowing into the troughs. The means herein shown consists of a longitudinal bar 12 fixed in seated relation to the bed 1 adjacent to each trough. The opposite ends of the bar 9 are turned upward so that they overlie said bars 12, as shown in Fig. 5.

What is claimed is—

1. In a carpet scrubbing mechanism, a bed 10 for the reception of a floor covering or a portion thereof, troughs located on opposite sides of and occupying a lower level than said bed, said troughs being adapted for the reception of coiled portions of such covering, 15 and means preventing drainage of cleansing fluid from said bed to said trough.
2. In a carpet scrubbing mechanism, a bed 20 for the reception in flatwise condition of a floor covering, or a portion thereof, a longitudinally extending trough located on each of the opposite sides of and occupying a lower level than said bed, means associated with said bed for preventing drainage of cleansing fluid from said bed to said troughs, 25 means for holding in fixed position an edge portion of a floor covering to prevent movement of said covering on said bed, and means located partially within said troughs for adjusting the position of said holding means.
3. In a device of the character described, 30 a bed for the reception in flatwise condition of a floor covering, or a portion thereof, a longitudinally extending trough located on each of the opposite sides of and occupying 35 a lower level than said bed, each of said troughs being adapted for the reception of a coiled portion of such covering, means for holding in fixed position an edge portion of a floor covering against movement of said

covering relative to said bed, and means for 40 adjusting the position of said holding means.

4. A support whereon floor coverings may rest while being cleansed, said support comprising a floor having formed therein in spaced relation and below the level thereof, 45 a pair of parallel troughs, the floor between said troughs being adapted to receive flatwise thereon a portion of the floor covering, and said troughs being adapted for the reception of coiled portions of such covering, 50 and means for preventing overflow of fluids to said troughs from the floor space between said troughs.

5. In a device of the character described, 55 a bed for the reception in flatwise condition of a floor covering, or a portion thereof, a longitudinally extending trough located on each of the opposite sides of and occupying a lower level than said bed, a bar provided with means for holding an edge portion of a floor covering whereby the latter is maintained against shifting movement on said bed, and means for adjusting the position of said bar.

6. In a device of the character described, 60 a bed for the reception in flatwise condition of a floor covering, or a portion thereof, a longitudinally extending trough located on each of the opposite sides of and occupying 65 a lower level than said bed, a bar provided with means for holding an edge portion of a floor covering whereby the latter is maintained against shifting movement on said bed, and shiftable holding means for said bar.

In testimony whereof, I affix my signature.

CARLOS A. SMITH.
